CODE SETTING DEVICE FOR SIGNAL SYSTEMS

Tellef A. Terjesen, Hoboken, N. J., assignor to Signal Engineering & Manufacturing Company, New York, N. Y., a corporation of Massachusetts

Application January 17, 1935, Serial No. 2,241

3 Claims. (Cl. 177—380)

The present invention relates to electrical signaling apparatus and systems of the type commonly employed for controlling, from a given point, the operation of various kinds of signal devices for sounding or displaying a multiplicity of different signals all in accordance with a predetermined code.

Ordinarily a signal system, of the above described type, comprises in addition to the signals themselves, a code determining or setting device cooperating with a code sending device, the function of the code setting device being to enable the operator to manually determine or set the code signal desired, whereupon the code sending device operates under the control of the setting device to automatically sound the selected predetermined signal sequence. In code setting devices, as heretofore constructed, the code determination has been obtained either by arranging electrical contacts in different code sequences, as shown in Burdick Patent No. 1,823,585, or by providing dissimilar mechanically operated code determining elements arranged in groups in accordance with the code sequences, as shown in Hanel Patent No. 1,969,978. While the code setting devices of the types shown by the aforementioned patents are satisfactory from an operating standpoint, the manufacture of such devices in quantity presents certain inherent difficulties, owing to the multiplicity of combinations that are required for the code determining contacts, or elements as the case may be.

According to the present invention, there is provided an improved code setting device characterized by the utilization of identical code determining elements that may be manufactured cheaply in large quantities and readily assembled in such manner as to set up the desired code combinations, in response to the operation of identical actuating or code setting members. The device of the present invention is further characterized by its certainty of operation and the fact that it is entirely free from electrical troubles due to the purely mechanical relation that exists between the code determining elements and their associated actuating members. The above and other advantageous features of the invention will hereinafter more fully appear from the following description with reference to the accompanying drawings, in which:

Fig. 1 is a view in front elevation of a code setting device embodying the invention.

Fig. 2 is a view of the device of Fig. 1, with

parts broken away to show details of construction.

Fig. 3 is a vertical sectional view of the device of Fig. 1, with the section taken along the first row of code determining elements.

Fig. 4 is a vertical sectional view similar to Fig. 3, with the section taken along the second row of code determining elements.

Fig. 5 is a transverse sectional view along the line 5—5 of Fig. 1.

Fig. 6 is a sectional view similar to Fig. 5, showing the operation of a code setting key.

Fig. 7 is a plan view of the device of Fig. 1, with its cover removed and showing diagrammatically, the electrical connections between a code setting and a code sending device.

Fig. 8 is a view, partly in front elevation and partly in section, of a modified form of code setting device.

Fig. 9 is a transverse sectional view along the line 9—9 of Fig. 8.

Fig. 10 is a sectional view similar to Fig. 9, showing the operation of the setting key.

Fig. 11 is a partial plan view of the device of Fig. 9, with the cover removed, and showing the electrical connections.

Like reference characters refer to like parts in the different figures.

Referring first to Fig. 1, the code setting device comprises a base 1 and a top section 2, between which are assembled a number of code setting units A and B arranged in stack relation, the units being similar in construction and each being adapted to determine a different group of code settings, as will hereinafter appear. Each unit provides a series of code setting members or keys 3 terminating in buttons 4 bearing different code designations, as shown in Fig. 1, and the code setting members or keys 3 are movable in slots 5 provided in a key plate 6 at the front of each unit, see Fig. 2.

As best shown in Figs. 3, 4 and 5, each unit provides a plurality of identical code determining elements 7 arranged in vertical rows and in horizontal series corresponding to the number of keys 3, with the elements of each row spaced apart by plates 6a that provide key slots in alignment with the slots 5 of the front key plate 6. Each code determining element 7 provides a slot 8 that is slightly longer than the slot 5 of a key plate 6, or 6a, and also is unsymmetrical with respect to the central axis of an element. It is also to be noted that since the over-all length of an element 7 is exactly the same as the depth of a key plate 6 measured vertically, the upper

end of a slot 8 will project into a key plate slot 5 when an element 7 is positioned with the longer end of its slot downward. Conversely, when an element 7 is positioned with the longer end of its slot 8 upward, the edge of this slot will be slightly above the key plate slot 5. A comparison between the first and second rows of code determining elements 7, shown in Figs. 3 and 4, will make clear the results that can be obtained by merely reversing the position of the code determining elements 7 in the units of the stack.

Referring now to Fig. 5, there is shown the particular arrangement of the code determining elements 7 to provide for setting up code combinations representing the call numbers "six" and "twenty-four", upon operation of the correspondingly designated keys 3. In the case of the lower series of elements 7, it is obvious that the slots 8 of the first six elements project into the aligned key slots 5, while with the second series of elements the slots of the first two elements project, the third element is clear, while the next four elements also project. It is evident then, that by merely positioning the elements 7 of each series with the longer ends of the slots 8 either up or down, any desired code designation can be obtained within the limit of the number of elements in a series.

As best shown in Fig. 5, each key 3 provides on opposite sides thereof a number of notches 9 corresponding to the number of code determining elements 7 in the series, with one side of each notch 9 being inclined, as indicated at 10. With the key 3 yieldingly maintained in its retracted position, as by means of a spring 11, the inclined notch faces 10 just bear on the edges of the projecting slots 8, but upon pushing in the key designated "twenty-four", six of the first seven elements 7 of the upper unit B will be raised, as shown in Fig. 6. Obviously, should this vertical shifting of elements 7 take place in the lower unit A it will be communicated to those elements directly above, in the stack, and the manner in which the setting of any elements 7, in accordance with the code designation of a depressed key, is utilized for control of a code sending device will next be described.

As best shown in Figs. 3 and 5, each row of code determining elements 7 of the top unit B has associated therewith a shift bar 12 providing the notches 12a corresponding to the number of elements 7 in the row, with each notch 12a offset with respect to the vertical center line of an element 7. The bars 12 are yieldingly held in position by springs 13 and with the keys 3 all retracted, there is no actual engagement between the elements 7 and a shift bar 12. Upon operation of a key 3, the beveled end of any element 7 which may be moved upwardly engages the nearest corner of a notch 12a to shift the corresponding bar 12 to the right, the engaged notch 12a tending to center itself on the end of the element 7. Thus, the depression of a key causes movement of only those shift bars 12 that are in line with the particular rows of elements 7 in which one element may be shifted in accordance with the code designation. For convenience of assembly, the shift bars 12 are loosely mounted on pins 14 extending across the top section 2 and are held apart by suitable spacers 2a forming part of the section 2.

The right hand end of each shift bar 12 is insulated where it bears on a flexible contact 15, and each contact 15 is opposed to, but slightly spaced from, one of a series of spaced stationary

contacts 16 on a bus bar 17 carried by the cover 2. Referring now to Fig. 7, the contacts 15-1 to 15-9 inclusive, are connected to stationary contacts 18-1 to 18-9 of a commutator 19 forming part of a code sending device, which may be of any desired type since it forms no part of the present invention. The bus bar 17, carrying contacts 16, is connected to one side of a suitable power source S, as indicated, so that shifting of one or more bars 12 by depressing a key 3 causes one or more of the commutator contacts 18 to be energized in accordance with the code determination. The commutator 19 also provides an arm 20 mounted on a shaft 20a so as to engage the commutator contacts 18, and since the arm 20 is connected to the other side of the source S through a suitable signal device 21, rotation of the commutator shaft will cause the signal 21 to be sounded in accordance with the code, as determined by a depressed key 3.

While the commutator 19 only provides nine coding contacts 18-1 to 18-9 inclusive, each code setting unit provides a tenth row of elements 7 cooperating with a shift bar 12 and movable contact 15-10. The purpose of this contact 15-10 is to start the operation of a suitable motor 22 for driving the commutator shaft 20a, upon full depression of a key, with provision being made for opening the contact 15-10 as soon as the motor starts, after which the motor turns 30 the arm 20 through one or more complete revolutions as determined by a control switch 23, operated from the commutator shaft 20a.

Referring again to Fig. 5, it is to be noted that the inclined face 10a of the last notch is less 35 steep than the other faces, thereby making it necessary to press the key 3 all the way in before the element 7 in the last row is lifted enough to cause the tenth shift bar 12 to close the motor starting contact 15-10. As a key 3 is pushed all 40 the way in, as shown in Fig. 6, an inclined projection 24 at the front end of the key raises a locking plate 25 which drops into place behind the projection 24 to prevent return of the key when it is released. The key 3 is shown in its 45 locked position of Fig. 6, from which it is apparent that while certain code determining elements 7 of the first nine rows will be held up in accordance with the disposition of their slots 8, the element in the last row will be released in 50 the locked position of the depressed key due to the low inclination of the face 10a. In other words, it is necessary to push a key 3 all the way in to give a starting impulse to the motor 23, with the starting circuit being interrupted upon 55 return of the key to locked position in which the code determination is set and held.

Following the depression and locking of a key 3, the key remains in this position until the depression of a key in the same or in another unit 60 of the device. With a key locked in the upper unit B as shown in Fig. 6, it is obvious that depression of a key in the lower unit will cause its inclined projection 24 to lift the lower locking plate 25, which movement is imparted to the locking plate immediately above. This has the effect of releasing a previously depressed key, so that there can be only one key depressed at a time. Furthermore, upon release of a key the shift bar springs 13 return the shifted bars and 70 their corresponding elements 7 to their original positions. In order to provide for lifting of the lower locking plate 25 upon operation of a key in the upper section, the locking plates 25 are secured together by lugs 25a, so they will move in 75

unison, and the plates are yieldingly held in locking position by the spring 26, see Fig. 2.

Referring now to Fig. 8, there is shown a modified form of the device, in which the code setting units A and B are constructed in exactly the same manner as shown in Fig. 1, with the omission of the keys cooperating with each series of elements. Instead of a series of keys there is provided a single master key K, which is insertable in any one of the series of aligned slots provided by the code determining elements. The cross-section of the key K is substantially the same as the size of the slots in the key plates 6 and 6a, so that when the key K is inserted in the slot designated "twenty-four" as shown in Fig. 10, the same code determining elements 7 are lifted that are shown lifted in Fig. 6 to form the code designation.

The element 7 in the tenth row which is adapted to control the starting contact of the code setting device, is lifted only when the key K is pushed all the way in, as indicated in dotted lines, due to the fact that the end of the key is beveled. After being pushed all the way in, the key K is retracted by means of a spring 27 carried by the key, which tends to maintain the key in the position of Fig. 10 to maintain the code setting while the code is being sent. The key K may be left in position after the sending of a round of signals, and if it is desired to send another round, it is only necessary to again push the key in to its extreme position to actuate the starting element.

As best shown in Fig. 11, the code determining elements of the top unit B cooperate with a series of shift bars 28 of a different form from the shift bars 12. Each bar 28 provides a series of slots 29 corresponding in number to the number of elements 7 of each row. The slots 29 are slightly larger than the beveled ends of the elements, and with the device in an unset condition as shown in Fig. 8, the right hand edge of each slot 29 lies closely adjacent to the one beveled surface of each element 7. Consequently, when the key K is inserted to raise a number of elements 7 in accordance with the code determination, as shown in Fig. 10, the raised elements will enter the slots 29 of the corresponding bars of each row, thereby causing these bars 28 to shift to the right as shown in Fig. 11. The tops of the bars carry insulating lugs 30, which upon shifting of any of the bars to the right cause the engagement of contact fingers 15-1 to 15-10 inclusive, with contacts 16 is provided by a bus bar mounted on the top 31.

As best shown in Fig. 8, the end walls 31a of the top provide slots 32 in which the shift bars 28 are assembled, and springs 33 serve to maintain all the bars fully retracted in the left hand slot 32, in the unset condition of the device. In this position the right hand slot 32 provides space for movement of the bars 28 to the right in order to operate the contacts in accordance with the code setting.

From the foregoing it is apparent that by the present invention there is provided an improved code setting device characterized by its simplicity and reliability in operation. Obviously, the device is particularly adapted for quantity production, owing to the fact that the code determining elements, shift bars and code setting members or keys are identical, and it is unnecessary to stock large numbers of parts having different forms. In other words, the particular code numbers to be set up by the device are determined en-

tirely by the manner of placing each element in its series, so that in assembling a device embodying the present invention, almost any code combination can be provided to meet a customer's requirements, without it being necessary to make up any special code determining elements. 5

I claim:

1. A code setting device comprising code determining members of identical shape and size and each symmetrical about a center line, each member having a slot therein which is offset with respect to said center line, means for mounting said members one behind the other in a series with their peripheries in alignment for independent shifting movement, certain of said members being mounted reversely to the other members whereby a common aligned slot is formed with the slot ends of said certain members projecting into the common slot and a code setting member movable in the common slot and having identical shifting portions for each of said members, whereby upon movement of said code setting member in said common slot the said certain determining members having their slot ends projecting into the common slot will be shifted 25 to compose the code.

2. A code setting device comprising code determining members of identical shape and size and each symmetrical about a center line, each member having a slot therein which is offset with respect to said center line, means for mounting said members one behind the other in a series with their peripheries in alignment for independent shifting movement, certain of said members being mounted reversely to the other members, 35 whereby a common aligned slot is formed with the slot ends of said certain members projecting into the common slot, and a code setting member movable in the common slot and having shifting portions for said determining members 40 equidistant from the axis of said common slot, whereby upon movement of said setting member in said common slot, the said certain determining members having their slot ends projecting into the common slot will be engaged by said setting 45 member and shifted to compose the code.

3. A code setting device comprising code determining members of identical shape and size, and each symmetrical about a center line, each member having a slot therein which is offset 50 with respect to said center line, means for mounting said members one behind the other in different series with their peripheries in alignment for independent shifting movement, certain of said members in each series being mounted reversely to the other members of the series, whereby a number of common aligned slots are formed, with the slot ends of said certain members in each series projecting into the common slot of the series, selector members corresponding in 55 number to the number of elements in each series and carrying operating portions common to correspondingly positioned elements in different series, and a code setting member movable in the common slot of a series, and having shifting portions for said members equidistant from the axis of said common slot, whereby upon movement of said setting member in said common slot, the said certain determining elements of that series having their slot ends projecting into the common slot, will be shifted to compose the code, together with selector members corresponding to the shifted determining elements. 70
